UNITED STATES PATENT OFFICE

PHILIP BERGMANN, OF PHILADELPHIA, PENNSYLVANIA, ASSIGNOR TO COLUMBIA STEEL EQUIPMENT COMPANY, OF PHILADELPHIA, PENNSYLVANIA, A CORPORATION OF PENNSYLVANIA

POSTING TRAY

Application filed October 26, 1927. Serial No. 228,849.

This invention relates to office appliances and in particular to posting trays of the type used by banks and other business establishments for containing account cards or sheets.

5 An object of the invention is to provide a posting tray with a side which may be transferred from a vertical to a horizontal position under the bottom of the posting tray without detaching the side from the posting tray.

10 Another object is to produce an efficient, strong and durable device of the class specified, which may be economically constructed.

15 Other objects and advantages will herein-after appear.

The views of the drawings are:

Figure 1 is a side elevation of a posting tray provided with a side constructed according to my invention, the side being shown 20 in its position beneath the bottom of the posting tray;

Figure 2 is a vertical transverse section;

Figure 3 is a vertical section through a corner of the posting tray, showing the side 25 raised and locked in position, the view being from the inside of the posting tray looking outwardly;

Figure 4 is a fragmentary perspective showing the retaining means for the side 30 when the side is in a vertical position;

Figure 5 is a section on line 5—5 of Fig. 2; and Fig. 6 is a section on line 6—6 of Fig. 2.

Referring to the drawings, the posting tray has a bottom 1, ends 2, a side 3 that is of 35 the same height as the ends 2, and a side 4 of lesser height. These parts may be formed of sheet metal and are welded together. The end portions of the side 4 are joined to the ends by upwardly-extending pieces 5 which 40 are longitudinally-directed terminal portions of flanges 5—a reverted in spaced relation upon the end walls 2. The purpose of the side 4 is to prevent sheets of paper or cards (not shown) from sliding laterally from the 45 posting tray when the device is in use.

At one end of the posting tray there is a 50 tilttable inner front member 6, of any approved construction.

Above the bottom 1 there is another bottom 55 7, the central longitudinal portion of which

consists of a channel member 8 in which is mounted a slideable back 9 (see application for United States Letters Patent filed by me September 17, 1927, Serial No. 220,171).

The bottom 1 is substantially Z-shaped in vertical section so that it has two elevations, a lower portion 10 that is slightly more than one-half the width of the posting tray, and a higher portion 11 that is connected to the lower portion by a narrow vertical web 55 12.

If so desired the bottom and side 4 can be made from a single piece of sheet-metal, bent to the form shown by Figure 2, while a substantially Z-shaped member 4a, illustrated in Fig. 2, may be employed to reinforce the uppermost bottom member 11.

The lower edges of the ends 2 are bent inwardly to form channels 13, which together with the space beneath the portion 11 of the bottom provide a pocket for receiving a side 60 14.

The side 14 has pins 15 projecting from the lower corners thereof, such pins being disposed in the channels 13.

The channels are so formed as to provide tracks for guiding the pins 15, and the bottom flanges of the channels support the ends 65 of the side 14.

Near each upper corner, the side 14 has 70 brackets 16 welded thereto. These brackets retain slidably mounted latches 17 formed by bending a strip of sheet-metal to the form clearly shown by Figure 4.

When the side 14 is in its vertical position 75 it may be locked in place by projecting the latches 17 outwardly so that they will engage the contiguous portion of the upwardly extending flanges 5 of the side 4, in the manner shown by Figure 3.

When the posting tray is not in use, the side 14 may be disposed in its vertical position. However, when the posting tray is in use, it is desirable that the side 14 be removed from its vertical position. To accomplish this, the latches 17 are slid inwardly and then the side 14 is dropped outwardly to a substantial horizontal position, it is then slid inwardly beneath the portion 80 90 95 100 100

11 of the bottom 1, to occupy the position shown by Figures 1 and 2.

The invention set forth herein is, of course, susceptible of various modifications and adaptations.

5 The invention claimed is:

1. In combination with a posting tray having ends, and a bottom so formed as to provide a longitudinal pocket beneath a portion of the posting tray and said ends, a removable side for the posting tray adapted to be transferred from a vertical position to

10 a substantially horizontal position in the said pocket, and means on said removable side adjacent the upper longitudinal extremities thereof, for locking it in its vertical position to said ends.

15 2. In a posting tray, a base member substantially Z-shaped in vertical section, the intermediate leg of which is narrower as

20 compared to the end legs, front and rear end walls, each having an inturned flange at the lowermost extremity, the uppermost of the legs of said base member and the said

25 flanges defining a recess, a removable side wall adapted to be swung from its normal position into said recess, said flanges being adapted to guide the side wall into and support it in position in said recess, an inturned

30 upstanding flange on one end of each of said end walls, locking means on said side wall, the last-named flanges and said locking means cooperating to secure said side wall in normal position.

35 3. In combination with a posting tray having ends, and a bottom so formed as to provide a longitudinal pocket beneath a portion of the posting tray and between said ends, a removable side for the posting tray

40 adapted to be transferred from a vertical position to a substantially horizontal position in the said pocket, an inturned upstanding flange on one end of each of said end walls and means on said removable side adjacent the upper longitudinal extremities thereof and coacting with said flanges for locking said removable side when in its vertical position to said ends.

PHILIP BERGMANN.
